Primary Examiner — John Windmuller(74) *Attorney, Agent, or Firm* — Banner & Witcoff, Ltd.(57) **CLAIM**

The ornamental design for a mop, as shown and described.

DESCRIPTION

FIG. 1 is a top, front, left perspective view of a mop showing our new design;

FIG. 2 is a front view thereof;

FIG. 3 is a rear view thereof;

FIG. 4 is a left side view thereof;

FIG. 5 is a right side view thereof; and,

FIG. 6 is an alternate perspective view thereof showing our new design in an exemplary environment.
The broken lines are for environmental purposes only and form no part of the claimed design.**1 Claim, 5 Drawing Sheets**(56)
